UNITED STATES PATENT OFFICE

FRED PAREIRA, OF NEW YORK, N. Y., ASSIGNOR TO HEALTH DEVELOPING APPARATUS CO. INC., OF NEW YORK, N. Y., A CORPORATION OF DELAWARE

ROWING MACHINE

Application filed June 6, 1932. Serial No. 615,684.

This application is a continuation in part of my copending application, Serial No. 602,692, filed April 2, 1932.

This invention relates to a rowing machine and has special reference to an apparatus for exercising in which a tensioning means is associated with a supporting frame to offer resistance to the energy exerted by a user as in rowing.

More particularly, this invention has reference to an apparatus comprising front and rear members connected together by side members, all of which members are preferably formed of sheet metal pressed into desired shapes for assembly into a frame to support a user, a tensioning means being associated therewith to offer resistance to the movements of the body of the user.

In the very nature of its use, the apparatus must be very strong and rigid since a very substantial force is exerted between the ends of the machine and since it must be capable of supporting a very substantial load. Generally, users of a machine of this character are overweight and make use of the apparatus for conditioning, although, of course, its advantages as a builder of weight are apparent. The combination, therefore, of the substantial weight of the user together with the force which the user employs in the exercises must be borne by the machine continually over a long period.

It is an advantage to provide a machine which is extremely light in weight for mobility since the apparatus is usually employed by individuals employed in offices and living in small apartments where space is at a premium and the machine must be stored in closets or under the bed. Therefore, a heavy cumbersome apparatus which is not readily moved besides being comparatively expensive is not desirable since it would be unsightly in appearance if permitted to remain in the open and awkward to move and to place if stored. The present device has the advantage of being of a strength and rigidity wholly capable of withstanding any strain that may be imposed thereupon, yet of a minimum weight and compactness that it may be stored without inconvenience.

Aside from its strength and lightness in weight, the cost of construction is held to a minimum and is greatly less expensive than prior art structures of which applicant is aware, the cost of the material being about one-fifth of the wood or cast constructions. After stamping and forming the members of the construction, no polishing or buffing is necessitated as in the cast construction, nor sanding and finishing as in the wood construction. Further, the sheet metal stampings may be welded together in a permanent rigid construction obviating the necessity for drilling, tapping and bolting as in the above mentioned constructions. Pieces bolted or otherwise secured together, further, are not permanent and need continual adjustment; whereas in the present construction, the welding is permanent and the life of the machine is indefinite.

The present invention contemplates the use preferably of a wholly sheet metal construction in which the material is of a very light-weight stock in which there is no sacrifice in strength yet a very material reduction in cost over the usual type of rowing machine. There has been a material reduction in the number of parts necessary for a complete machine and a consequent reduction in cost of assembly and material. The front frame member is extended upwardly to give the correct positioning of the tensioning members with the result that a single stamping is only necessitated. Certain deformations in the material of the frame members give the necessary rigidity to the construction which obviates the necessity for heavier stock.

The provision of grooved portions in the inverted U-shaped tracks over certain lengths gives a required strength that obviates the necessity for heavy castings or solid wooden rails. It may also be stated that there is less friction imparted to the usual rubber wheels of the movable seat in the use of the inverted U-shaped rails than the cast or wooden rails adding to the life of the wheels when a movable seat is employed. Further, wooden rails warp and make it impossible for the wheels to track correctly.

One of the objects of this invention is to

provide a rowing machine which is comparatively inexpensive to manufacture, is durable, is light in weight, and is compact in form.

Another object of this invention is to provide a rowing machine formed of sheet metal in which the elements thereof are capable of connection by welding.

Other objects and advantages will herein-after be more particularly pointed out and 10 for a more complete understanding of the characteristic features of this invention reference may now be had to the following description when taken together with the accompanying drawings, in which latter:

15 Figure 1 is a top plan view of the rowing machine embodying the features of this invention;

Fig. 2 is a side elevational view of Figure 1, showing in dotted lines a seat member 20 thereon;

Fig. 3 is a transverse sectional view taken on the line 3—3 of Figure 1;

Fig. 4 is a bottom plan view of Figure 1;

Fig. 5 is a longitudinal central sectional 25 view of a fragmentary portion of the rowing machine shown in Figure 1 taken on the line 5—5 thereof;

Fig. 6 is a view similar to Fig. 5, taken on the line 6—6 of Figure 1;

30 Fig. 7 is a transverse sectional view taken on the line 7—7 of Fig. 2;

Fig. 8 is a fragmentary sectional view taken on the line 8—8 of Fig. 2;

Fig. 9 is a fragmentary sectional view 35 taken on the line 9—9 of Fig. 7; and

Fig. 10 is a perspective view of the adjustable connection for the strap member.

Referring now more particularly to the drawings, the device of this invention 40 comprises a rear frame member 1, a front frame member 2, and side rail frame members 3. Suitably guided in the front frame member is a flexible connection 4 intermediate an operating handle 5 and a spring or springs 6 45 connected to the rear frame member.

In the present embodiment, the frame members are so formed and related they may be welded together to comprise a unitary rigid sheet metal structure, the upper surface of 50 each side rail being channelled or dished, to receive rollers of a seat, the latter being indicated by dotted lines at 7, Fig. 1.

The front frame member is formed of a single sheet of metal having opposed openings at 8 forming a plurality of arms 8a which are inclined upwardly in advance of a horizontal plate-like section 2a. The edges of arms 8a are bent down to form flanges 8b and the side margins of the plate-like section 2a are bent downwardly to form continuing flanges of the flanges 8b of the outer arms. Opposed flanges 8b of the center arm 8a are apertured to receive a bearing member shown in the form of a stud 9 headed at one 60 end and threaded at the opposite end to re-

ceive a nut 10, the stud serving as a bearing for a preferably channelled roller 11 for receiving a tensioning member in the form of a flexible connection 4, in the present embodiment, a strap. The transverse marginal edges 70 of the plate-like member 2a are bent downwardly to form flanges 2b and 2c, the flanges 2b being formed continuously with the inner flanges 8b of the arms 8a.

The upper front portion of the front frame member is provided with a central depression by pressing in the metal to form opposed flanges 12, these flanges being apertured to receive stud 13 headed at one end and threaded at the other end to receive a nut 14, the stud 13 serving as a bearing for a channelled roller 15 which receives a flexible connection 4 and guides the same over the top of the frame members.

The studs 9 and 13 may also serve to hold 80 in position a guiding means in the form of a guard plate 16, the latter being U-shaped in cross section.

Side rails of the device are metallic members each formed of a plate bent to inverted U-shaped cross section, the top of the member of each rail being depressed to form a runway 3a for the rollers of a seat indicated in Figure 1 in dotted lines at 7. It will be noted that the guideways preferably extend only between points intermediate the front and rear frame members and not over the entire length thereof for rigidity.

Each side rail 3 is placed so that the runway 3a lies uppermost, as shown in Fig. 6, 100 and one depending flange of the rail is placed adjacent the flange 8b and is secured thereto by welding, riveting or both. In the present embodiment, the connection is preferably by welding. In addition to welding the side rail to a side flange of the front frame member, it may be welded to the undersurface of 105 said member or may be riveted thereto.

The rear frame member 1 comprises a sheet of metal formed with an inwardly extending flange 1a, inwardly extending side flanges 1b and preferably, an inwardly extending bottom flange 1c, as shown more particularly in Fig. 7. The metal of frame member 1 is inwardly depressed to provide a shoulder 17 which shoulder is perforated with annular openings at 18, each opening merging into a slot which runs down into the metal below the shoulder.

The flexible connection 4 at its rear end is 120 carried by a socket member 19 which receives the headed ends of attaching members carried by springs 6. At its rear end, each spring 6 carries a headed attaching member 20, the head of each attaching member being slightly less in diameter than one of the annular openings 18 and the shank of the attaching member being of slightly less diameter than the width of the slot which merges into the annular openings. There- 125

fore, the head of the attaching member 20 may be passed through an annular opening 18 and then moved downwardly so that the shoulder acts as a latching shoulder to hold the attaching member in position as shown in Fig. 5.

Each side rail 3 is moved upwardly until its top meets the upper flange of the rear frame member and one side of the rail abuts a side flange of the rear frame member and in such position the rail is secured to the top and side flanges, preferably by welding.

Both frame members may have supporting feet or legs connected thereto. As to the front frame member, each leg may comprise an L-shaped bracket 21a welded to the flange 8b as shown in Fig. 4 and having secured thereto by any suitable means such as a bolt 22b, a foot 23a of rubber or other suitable material.

In the case of the rear frame member, the legs or feet 24 are of rubber or other material and may be secured directly to the lower flange of said frame member.

In order to gain the advantage of lightness in weight in the use of a comparatively thin stock, the plate-like member, on which the entire weight of the user is disposed in the employment of the machine in several of its conditions of use, is provided with deformations 21 pressed out of the material of the member. These deformed portions may, as shown in the drawings, extend longitudinally and transversely of the member although the formations may be varied considerably and achieve substantially the same result. Also, the arms 8a are preferably provided with longitudinally extending deformations 22 from and preferably including a portion of the plate-like member to the upper ends thereof.

In order to give the necessary correct positioning of the tensioning member and at the same time provide for a single stamping, the front end of the front frame member is inclined upwardly to receive the upper roller member which changes the direction of pull on the tensioning means. It will be noted from the showing in Fig. 2 that the handle 5 is pulled in the opposite direction from the direction of pull of the coil springs 6 and directly against the front end of the frame member and that the strain against the forward end of the casting, therefore, is a substantial one. By reason of the construction of the application, the force exerted against the front end may be withstood indefinitely by a comparatively light weight stock of material.

It will be seen that in the device, the side rails are suspended by the front and rear frame members and that the front frame member lies above the side rails, the latter being within the flanges of the front frame member and lying within the flanges of the rear frame member.

In the use of the machine, the opposed openings in the front frame member are preferably bounded at their tops by a cross-bar against which the feet of the user rest and clearance is given for the heel portion 70 of each foot by said openings. Flanged metal surfaces on the edges of the crossbar, preferably formed continuously with the flanges of the arms, strengthen the structure and provide smooth surfaces. The outer and upper flanges of the inclined front section of the frame member strengthen the device and afford a pleasing contour. By depressing the metal at the top of the inclined section of the front frame member to form opposed flanges, 76 80 a novel seat and bearing connection for the guide roller is provided without the necessity of applying brackets.

It will also be noted that the inner flanges of the opposed recesses and upwardly inclined section of the front frame member afford protection over the lower guide roller.

Also, by forming an upper shoulder in the rear frame member provided with an annular aperture merging into a slot formed in the metal below the shoulder, an ideal means of attachment is provided for the headed stud of the spring or springs. The primary elements of the structure, that is to say, the front and rear frame members and side rails, 86 90 95 are so formed that they may be pressed out of a single piece of sheet metal.

Another feature of this invention resides in the provision of an adjustable attachment between the socket member 19 or the multiple spring catch and the flexible connection or webbing 4. In prior constructions, so far as applicant is aware, the webbing passes through a loop of the connecting member and the end thereof is fixedly attached to an intermediate portion of the webbing by means of eyelets or stitches. A single thickness of webbing, therefore, contacts directly with the metal which ordinarily is a sheet metal clamping having sharp edges. The webbing becomes worn in a comparatively short time and breaks, necessitating stitching or otherwise securing the same by the user who does not necessarily have the proper facilities for this repair. Ordinarily, the strap with the attached handle and attached multiple spring catch are sent back to the manufacturer to have the repairs made or the strap replaced. In the present construction, 100 105 110 all that is necessary for a user to do is to write for a new strap.

In the present invention a double thickness of webbing is passed through the opening of the connecting member 19 and is adjustably connected thereto whereby any wear may be taken up in the strap and the strap shortened or lengthened, as desired, for specific exercises. In further explanation of this latter statement, there are various exercises which demand a longer strap than others 115 120 125 130

and, conversely, some exercises require a much shorter strap than others. Therefore, it is very much to be desired that the strap be conveniently and readily adjustable to

5 the tensioning means, and/or to the handle.

Referring now more particularly to Fig. 10 of the drawings, the multiple spring catch 19 preferably comprises a sheet metal stamping formed with a plurality of apertures 22a 10 for receiving headed ends of the spring members 6. The member 19 is substantially L-shaped having an aperture 23 at one end thereof, the other end lying in the same plane and having enlarged openings of sufficient 15 size to receive the heads of the springs 6. The transverse portion of the member 19 lying between the end portions 25 is sufficiently wide to receive the heads of the screws and the apertures are extended from the enlarged 20 opening 24 across the transverse portions to permit the shank adjacent the head of the springs to pass, thereby providing for a detachable engagement between the spring members 6 and the member 19.

25 The strap 4 is threaded through a link 26 and thence through the opening 23 in the member 19 back through the link and forwardly through the aperture 23 to have the free end of the strap threaded again through

30 the link 26. A pull, therefore, on the strap 4 binds the link 26 against the end of the member 19 and prevents disengagement of the strap and the member. It will also be noted that an aperture may be provided in

35 the handle 5 for the same purpose that the aperture 23 is provided in the member 19, whereby an adjustable connection between the strap and handle is provided. It will be further noted that there are two thick-

40 nesses of the strap which pass through the aperture 23 and that by merely allowing a certain amount of slack in the strap 4, the link 26 may be pulled away from the end of the member 19 whereby the strap may be

45 threaded further into the link, or may be pulled thereout to provide any length of strap.

While but a single embodiment of this invention is herein shown and described, it 50 is to be understood that various modifications thereof may be apparent to those skilled in the art without departing from the spirit and scope of this invention and, therefore, the same is only to be limited by the scope 55 of the prior art and the appended claims.

I claim:

1. A rowing machine comprising a front frame member, a rear frame member, sides connecting said front and rear frame members, said front frame member being formed of sheet metal having an upwardly inclined front portion with at least one opening forming a plurality of flanged arms, said arms having longitudinally extending deformed 60 portions intermediate the sides thereof, guid-

ing means on said front frame member, a foot rest disposed on said arms and supported thereby, and tensioning means passing over said guiding means.

2. A rowing machine comprising a front frame member, a rear frame member, sides connecting said front and rear frame members, said front frame member being formed of sheet metal having an upwardly inclined front portion with at least one opening forming a plurality of flanged arms, guiding means on said front frame member a foot rest disposed between said flanged arms and supported thereby, and tensioning means passing over said guiding means. 70

3. A rowing machine comprising a front frame member, a rear frame member, sides connecting said front and rear frame members, said front frame member being formed of sheet metal having an upwardly inclined front portion with opposed openings forming a plurality of arms having flanges on the opposed sides thereof, said arms having longitudinally extending deformed portions intermediate the flanges thereof, guiding means on said front frame member, a foot rest disposed between said flanged arms and supported thereby, and tensioning means passing over said guiding means. 75

4. A rowing machine comprising a front frame member a rear frame member, sides connecting said front and rear frame members, said front frame member being formed of sheet metal having a plate-like rear portion and an upwardly inclined front portion with at least one opening forming a plurality of flanged arms, said arms having longitudinally extending deformed portions intermediate the sides thereof extending from said plate-like portion, said plate-like portion having deformed portions within the outer confines thereof, guiding means on said front frame member, and tensioning means passing over said guiding means. 80

5. A rowing machine comprising a front frame member, a rear frame member, sides connecting said front and rear frame members, said front frame member being formed of sheet metal having a plate-like rear portion and an upwardly inclined front portion with opposed openings forming a plurality of arms with flanges on the edges thereof, said plate-like portion having flanges on all sides thereof with the forward flanges thereof being continuous with the flanges of said arms, a foot rest disposed between said arms and supported thereby, guiding means on said front frame member and tensioning means passing over said guiding means. 110

6. A rowing machine comprising a front frame member, a rear frame member, sides connecting said front and rear frame members, said front frame member being formed of sheet metal having a flanged plate-like rear portion and an upwardly inclined front por-

tion with at least one opening forming a plurality of flanged arms, a foot rest formed of sheet metal and supported by said flanged arms, guiding means on said front frame member, and tensioning means passing over said guiding means.

7. A rowing machine comprising a front frame member, a rear frame member, sides connecting said front and rear frame members, said front frame member being formed of sheet metal having an upwardly inclined front portion with at least one opening forming a plurality of flanged arms, guiding means supported by said arms and disposed between the flanges thereof, and tensioning means passing over said guiding means.

8. A rowing machine comprising a front frame member, a rear frame member, sides connecting said front and rear frame members, said front frame member being formed of sheet metal having an upwardly inclined front portion with opposed openings forming a plurality of flanged arms, a roller supported by one of said arms and disposed between the flanges thereof, a guide plate supported by said last mentioned arm and disposed between the flanges thereof adjacent said roller, and tensioning means passing over said roller and under said guide plate to be held against displacement thereby.

9. A rowing machine comprising a front frame member, a rear frame member, sides connecting said front and rear frame members, said front frame member being formed of sheet metal having an upwardly inclined front portion with opposed opening forming a plurality of flanged arms, a roller supported by one of said arms and disposed between the flanges thereof, a flanged guide plate supported by said last mentioned arm and disposed between the flanges thereof adjacent said roller, and tensioning means passing over said roller and under said guide plate between the flanges thereof to be held against displacement thereby.

10. A rowing machine comprising metallic side rails, U-shaped in formation, a rear frame member having side flanges, a front frame member formed of a sheet of metal having a platelike rear section and an upwardly bent front section, the latter being formed with opposed apertures having downwardly extending flanges and the side margins and top of the frame member being made with similar flanges, tensioning means connected to the rear frame member, guiding means carried by the front frame member for said tensioning means, the side rails being connected to the front frame member within its flanges and below its upper surface and having connection with the rear frame member.

11. A rowing machine comprising a frame having front and rear members, U-shaped rails connecting said members, said rails and

said members being formed of sheet metal, said front frame member having an upwardly inclined front portion with opposed openings forming a plurality of flanged arms, a foot rest and guiding means disposed between said flanged arms and supported thereby, said rear frame member being flanged for connection with a side and the top wall of each of said rails, and tensioning means secured to said frame and extending over said guiding means.

12. A rowing machine comprising a frame having front and rear members, U-shaped rails connecting said members, said rails and said members being formed of sheet metal, said front frame member having an upwardly inclined front portion with opposed openings forming a plurality of flanged arms, a foot rest and guiding means disposed between said flanged arms and supported thereby, said rear frame member being flanged for connection with a side and the top wall of each of said rails, and having key slots therein, and tensioning means having headed studs for detachable engagement with said key slots.

13. A rowing machine comprising a front frame member, a rear frame member, side rails connecting said front and rear frame members for receiving the wheels of a movable seat, each of said rails being of sheet metal of inverted U-shaped cross-section and extending within the confines of said front and rear frame members to be connected thereto, the upper edge of said U-shaped rails being dished over the longitudinal length of said rails, a foot rest and guiding means on the front frame members, and tensioning means passing over said guiding means.

14. A rowing machine comprising metallic side rails, U-shaped in formation, a rear frame member having side flanges, a front frame member formed of a sheet of metal having a platelike rear section and an upwardly bent front section, the latter being formed with opposed apertures having downwardly extending flanges and the side margins and top of the frame member being made with similar flanges, a spring connected to the rear frame member, a handle, a flexible connection intermediate the spring and the handle, guiding means carried by the front frame member for said flexible connection, the side rails being connected to the front frame member within its flanges and below its upper surface and having connection with the rear frame member.

15. A rowing machine comprising a rear frame member, a front frame member, rails connecting said members, a spring carried by the rear frame member, a handle and a flexible connection intermediate the handle and the spring, a front frame member being formed of sheet metal having a plate-like

rear section and an upwardly inclined front section, the front section being formed with opposed apertures, the metal at the margins of the apertures being downwardly flanged 5 and the side and top margins of said front frame member being downwardly flanged, a guide roller having a bearing between opposed flanges at said apertures and a guide roller at the top of the apertures, the flexible connection being led over said guide rollers.

16. A device constructed in accordance with claim 15 including a guide plate held intermediate the flanges which support the 15 lower guide roller and held in position by the bearing for said guide roller.

17. A rowing machine comprising front and rear metallic frame members each formed of a single piece of sheet metal, side 20 rails connecting said frame members, each rail being formed with a piece of sheet metal bent to form a hollow body comprising depending side walls and an upper wall, the upper wall being channeled to provide a 25 runway for seat rollers, the rear frame member being formed with vertical and horizontal flanges welded to the side rails, the front frame member being formed with vertical flanges welded to the side rails, the front 30 frame member comprising a rear plate-like structure and a forward upwardly inclined structure having opposed apertures bounded by downwardly extending flanges, a spring carried by the rear frame member, a handle, 35 a flexible connection intermediate the handle and the spring, and a guiding device carried by the front frame member for the flexible connection.

18. A rowing machine comprising a frame 40 member, tensioning means having one end connected to said frame, a flexible member extending from said tensioning means, an attaching member having an aperture and an adjustable connection for said flexible member for determining the length thereof comprising a closed link, said flexible member 45 extending through said link and through said aperture in said attaching member, thence back through said link and forwardly there- 50 over through said aperture with the free end passing through said link.

19. A rowing machine comprising end members, side members connecting said end members, one of said end members being 55 formed of sheet metal having a deformed portion on an upwardly extending wall thereof, said deformed portion forming a shoulder at the point of extension thereof from said wall, said wall having an enlarged opening 60 communicating through said shoulder with a reduced slot extending at least to said shoulder, and tensioning means, including a headed member connected thereto, said head being adapted for insertion through said opening, the portion of said member adjacent said

head being adapted for movement in said slot to a position such that said head will be held against displacement by said shoulder.

20. A rowing machine comprising a front frame member, a rear frame member, side 70 rails connecting said front and rear frame members, said rear frame member comprising a sheet metal stamping having flanges extending angularly therefrom for engagement with said side rails, the upwardly extending wall of said rear frame being deformed between the flanges thereof, and a tensioning member connected to said wall.

In witness whereof, I have hereunto subscribed my name.
